UNITED STATES PATENT OFFICE.

MOSES C. JOHNSON, OF HARTFORD, CONNECTICUT, ASSIGNOR TO THE HELIX GEAR COMPANY, OF SAME PLACE.

DESIGN FOR A GEARING-COVER FOR VEHICLE-FRAMES.

SPECIFICATION forming part of Design No. 31,824, dated August 1, 1899.

Application filed July 5, 1899. Serial No. 722,881. Term of patent 14 years.

To all whom it may concern:

Be it known that I, MOSES C. JOHNSON, a citizen of the United States, and a resident of Hartford, in the county of Hartford and

5 State of Connecticut, have invented a new and original Design for a Gearing-Cover for Vehicle-Frames; and I do hereby declare the following, when taken in connection with the accompanying drawings, to be a full, clear, and 10 exact description of the same, and said drawings constitute part of this specification, and represent, in—

Figure 1, a view in side elevation of the gearing-cover; Fig. 2, an end view, in front elevation, of the gearing-cover; and Fig. 3, an end view, in rear elevation, of the gearing-cover.

15 My invention relates to a design for covers for gearing, which as a whole is a special article of manufacture and adapted to be connected to or form part of the frame of a bicycle or like vehicle. The structure when so used comprises a cover for the crank-shaft, for the connecting-shaft, and for the gearing at the crank-hanger and also at the rear end of 20 the frame; and my said invention consists in the configuration of the structure, as herein-after described, and shown in the drawings.

25 The structure as a whole comprises a circular part *a* as viewed in side elevation, a circular part *b* of smaller diameter, and an elongated central portion *c*, extending from below the part *a* to a point above the part *b*, the en-

larged ends *d* and *e* of this part *c* being cylindrical in outline and having walls which merge into the walls of the parts *a* and *b*, re- 35 spectively.

When viewed in front elevation, as in Fig. 2, the part *a* appears as cylindrical in outline, with a portion *a'* of smaller diameter than the front portion, below which the circular end of 40 the part *d* appears.

When viewed in rear elevation, the oblong outline of the short cylindrical part *b* is surrounded by the circular outline of the end of the part *e*, the walls of these two parts merging 45 into each other.

The essential feature of my design is the arrangement of the gear-covers *a* and *b*, the former larger in diameter than the latter, with the connecting parts *d* *c* *e* extending diagonally across between the parts *a* and *b*, the part *d* underlying the part *a*, and the part *e* overlying the part *b*. 50

I claim—

20 The design for a gearing-cover for vehicle-frames substantially as shown and described. 55

In witness whereof I have signed this specification in the presence of two subscribing witnesses.

MOSES C. JOHNSON.
